UNITED STATES PATENT OFFICE.

THEODORE WILLARD CASE, OF SCIPIO, NEW YORK, ASSIGNOR TO CASE RESEARCH LABORATORY INCORPORATED, OF AUBURN, NEW YORK, A CORPORATION OF NEW YORK.

PHOTO-ELECTRIC CELL.

Application filed April 26, 1921. Serial No. 464,738.

To all whom it may concern:

Be it known that I, THEODORE WILLARD CASE, of Scipio, in the county of Cayuga, in the State of New York, have invented 5 new and useful Improvements in Photo-Electric Cells, of which the following, taken in connection with the accompanying drawings, is a full, clear, and exact description.

This invention relates to a new and im- 10 proved photo-electric cell.

It is well known that certain colors have a greater effect upon the human eye than others, or perhaps reversely, the human eye is more sensitive to certain colors than to 15 others, and specifically, the human eye seems to be more sensitive to the yellow and green than to the red, blue and violet.

There has recently been developed a solution 20 that permits the passage of light rays in proportion to the color sensitivity of the human eye, or the color effect of light rays upon the human eye.

By the apparatus and process of my co-pending application, Serial No. 430,095, 25 filed Dec. 11, 1920, I am able to plot, or produce a curve of light intensity, but said curve is dependent somewhat upon the character, or particular sensitivity of the light sensitive element used, and is, therefore, a 30 curve showing variations in the particular light sensitive element used as caused by variations in light intensity to which it is exposed, for it is found that even light reactive materials are of greater sensitivity 35 in some portions of the spectrum than in others.

It would be desirable to produce by my apparatus what I term a luminosity curve, that is, a curve of light intensity which will 40 indicate more clearly the effect of the existing light upon the human eye, or the actual light as interpreted by the human eye.

This result can be approximately accomplished in a preferred manner by utilizing 45 a photo-electric cell which itself interprets light as nearly like the human eye as possible combined with a screen, or filter material which permits passage of light to the light sensitive material, or cell, in approximate proportion to its effect upon the human eye.

My best information at this time is that 50 a photo-electric cell in which the light sensitive elements consists of, or comprises barium, is best suited for the purpose, as its

interpretation of light rays is more nearly like that of the human eye than any other practical material known to me.

This photo-electric cell may be formed in the manner described in my co-pending application Ser. No. 406,463, filed August 27, 1920, or in any other suitable manner, as for instance, by the distillation of barium within the vacuum tube of the cell.

However, any suitable photo-electric cell 65 may be used and material advantages are attained when practically any photo-electric cell is combined with a luminosity screen, or filter, and I do not desire to limit myself to the preferred combination of elements which I have discovered, except where 70 specifically set forth in the appended claims.

It will be understood that the luminosity screen, or filter, may be formed separately 75 from the vacuum bulb, and may be applied thereto, or confined or enclosed thereabout in any suitable manner so that the light rays must pass through it before striking the light sensitive element.

However, at present, I prefer to form the vacuum bulb of the photo-electric cell it- 80 self of a glass material that itself constitutes a luminosity screen, or filter, and through which the light rays must pass before striking the light sensitive element of the cell.

In the drawings:-

Figure 1 illustrates an embodiment of 90 my invention.

Figure 2 illustrates a somewhat different embodiment of my invention.

Figure 3 illustrates a further modified embodiment of my invention.

In the drawings in Figure 1 I have dis- 95 closed an ordinary photo-electric cell embodying a cathode —8—, an anode —9— and a transparent bulb —15—, which in this instance, is formed of glass of such character as to permit passage of light rays 100 in proportion to the color sensitivity of the human eye. The bulb —15— may be formed of any glass material that gives a spectral transmission curve similar in shape to the accepted visibility curve of the average eye. For illustration, the bulb may be made up of a combination of two glasses. One of these glasses is a shade of yellow and the other a green. The yellow glass used is known as "Corning high transmis- 105

sion yellow" and is, for instance, about 42 one-thousandths of an inch in thickness, while the green glass is "Corning 401 BJ" and may preferably be about 66 one-thousandths of an inch in thickness. This detailed specification is for illustrative purposes only.

I have illustrated the photo-electric cell of this invention as connected in the circuit 10 of the well known Leeds & Northrup self-balancing potentiometer disclosed in my co-pending application Serial No. 430,095, and which comprises two circuits connected with opposite polarity so that the two E. M. F.'s 15 oppose each other. Measurements are made with the potentiometer by varying a known electro-motive force until it equals the unknown. When the two are equal, the index of the potentiometer-galvanometer needle, 20 stands motionless. This needle is the controlling means of the recording apparatus.

The potentiometer is of the split-circuit, slide-wire type. The battery —1—, which 25 may consist of a few dry cells supplies continuously flowing current to the potentiometer circuit, the current being maintained constant by rheostat —2—. As the voltage in the battery —1— changes, the current in the potentiometer circuit will also change. 30 To compensate for this change, a portion of the battery voltage is compared at intervals with the constant voltage of the standard cell —3—, and the rheostat —2— is adjusted until the proper current is flowing. This is 35 accomplished by completing the circuit at —4— which connects the galvanometer —5— in series with the standard cell across the resistance coil —6—. If the voltage 40 across the coil is not equal to the voltage of the standard cell, the galvanometer will deflect from its zero position in which case the rheostat —2— should be adjusted until the galvanometer returns to its zero position. The voltages are now equal and 45 opposite, and the proper current flowing.

A battery —7— of suitable electromotive force is connected in circuit across the electrodes —8— and —9— of the photo-electric cell, which cell may, preferably, be manufactured in accordance with the disclosure 50 of my co-pending application Serial No. 406,463, above referred to, and the photo-electric element as —8— should preferably consist of or comprise barium.

55 A variable resistance —10— is inserted in the circuit between the electrodes of the photo-electric cell so that there is a drop in potential between the points —11— and —12— causing a flow of current through 60 the circuit thus formed. In addition the current flows through the photo-electric cell to the contact —13— which contact is movable with respect to the slide wire —14— 65 the current returning through the galvanometer —5— to battery —7—. Variations in

the current flowing in this circuit effected by variations of resistance in the photo-electric cell will cause deflection of the galvanometer needle, but the needle will again return to its zero position when a proper 70 adjustment of the slide-wire with respect to contact —13— is made, so that the current flowing in the two circuits balances each other.

The resistance —10— should be made adjustable so that if any variations in the sensitivity of the photo-electric cell occur by reasons of use or variation in manufacture, the resistance may be used to account for such variations. The movement of the galvanometer effected by variations in the current in the photo-electric cell circuit is utilized to control the recording mechanism. The operation of the Leeds & Northrup recorder is well known and need not be here 85 further described.

In the structure illustrated, the bulb —15— is formed of glass of such a character as to permit the passage of light rays in proportion to the color sensitivity of the 90 human eye, or approximately that proportion.

In Figure 2 I have disclosed a photo-electric cell of similar construction, except that the ordinary glass bulb —16— may be 95 utilized and may be provided with a coating, layer or enclosure of material having the same, or substantially the same characteristics as the glass of the bulb of Figure 1. This photo-electric cell, for illustrative purposes, is shown as connected in circuit with a source of potential —17— and a galvanometer —18—.

In Figure 3 a similar photo-electric cell is disclosed, such cell being enclosed in an additional casing of somewhat larger size so as to form a chamber between the bulb —18— of the photo-electric cell and the enclosing bulb, or casing —19—, within which chamber a luminosity solution may be confined in such a manner that the rays of light must pass therethrough before coming into contact with the sensitive element of the photo-electric cell.

115 It will be understood that the structures disclosed are merely illustrative of embodiments of my invention, which invention is capable of assuming various forms, the preferred embodiment being as set forth, the combination of a photo-electric cell including a light sensitive element consisting of or comprising barium, with a luminosity filter, that is, a filter which permits the passage of light rays in approximate proportion to the color sensitivity of the human eye.

120 However, my invention is much broader than its present preferred embodiment, and the annexed claims are deemed to include any photo-electric cells that react to light 130

rays in approximately the same sensitivity proportion as the human eye reacts to the same rays whereby a luminosity record or curve can be produced, and particularly the combination of a photo-electric element with a luminosity filter that permits the passage of light rays to said element in approximate proportion to the effect of said rays upon the human eye.

10 I claim:

1. A photo-electric cell in which the light sensitive element is provided with a filter through which rays of light pass to reach the light sensitive element, said filter permitting the passage of light rays in proportion to the color sensitivity of the human eye.
- 15 2. A photo-electric cell in which a light sensitive element including barium is provided with a filter through which rays of

light pass to reach the light sensitive element, said filter being formed of a material which permits the passage of light rays in substantial accordance with the color sensitivity of the human eye.

3. A photo-electric cell including a light sensitive element and a bulb enclosing the element, and through which rays of light pass to reach the element, said bulb being formed of glass material which permits the passage of light rays in substantial accordance with the color sensitivity of the human eye.

In witness whereof I have hereunto set my hand this 20th day of April, 1921.

THEODORE WILLARD CASE.
